UNITED STATES PATENT OFFICE

2,614,205

ILLUMINATING DEVICE FOR INSTRUMENT PANELS

John M. Roper, Washington, D. C., and Thomas O. Twist, Chevy Chase, Md.

Application September 21, 1948, Serial No. 50,342

2 Claims. (Cl. 240—2.1)

(Granted under the act of March 3, 1883, as amended April 30, 1928; 370 O. G. 757)

1

The present invention relates to an instrument lighting system, and more particularly to an instrument lighting system adapted for use in vehicular instrument panels, and especially in aircraft instrument panels.

It is the general practice in providing a cover or shield for instrument lighting to employ a single cover hand tailored for all lighting arrangements. It has been found that this type of shield has many disadvantages both in production and in actual use. Thus, in production, great care must be taken in tailoring the cutouts to properly fit the individual instruments or the entire panel will be practically useless. Furthermore, a different cover is required for each specific arrangement of instruments. Still further, if it is desired to rearrange the instruments on the mounting panel, a new shield will be necessary. Continued use of the single cover often results in buckling of the cover thereby disrupting the efficient operation of the system.

An object of the present invention is the provision of an instrument lighting cover designed for fitting to an individual instrument.

Another object is to provide an instrument lighting cover for an individual instrument that is adapted to be relocated as required when the position of the instruments are changed.

A further object of the invention is the provision of an instrument lighting cover having electrical connections from a source of voltage to the lamps when the cover is secured.

Still another object is to provide an instrument lighting cover having means for preventing glare from being reflected up from the bevel surface at the bottom of the instrument.

The exact nature of this invention as well as other objects and advantages thereof will be readily apparent from consideration of the following specification relating to the annexed drawing in which:

Fig. 1 illustrates a front elevational view of a portion of an instrument board showing an instrument and a preferred embodiment of the cover of the present invention.

Fig. 2 is a rear elevational view of the cover of Fig. 1.

Fig. 3 shows a side elevational view of the cover of Fig. 1.

Fig. 4 shows a section of the instrument board taken on the line 4—4 of Fig. 1.

Fig. 5 is a rear elevational view similar to Fig. 2 illustrating a modification of electrical connections.

Referring now to the drawings, wherein like 55 may be made of any suitable material, preferably

2

reference characters designate like or corresponding parts throughout the several views, there is shown in Fig. 1 a portion of a grounded instrument mounting panel 11, of conventional type, having an instrument 12 and an individual cover or shield 13 mounted thereon. Cover 13 is retained over the instrument by means of lugs 14, or any other suitable fastening means, and has a conventional lamp socket 15, as disclosed in Grimes Patent No. 2,401,867, mounted in each upper corner thereof, the lamps 16 being disposed rearwardly of the shield as shown in Figs. 2 and 5.

Cover 13 has its upper portion beveled as shown at 17 in order to more closely surround the instrument face and to more evenly distribute the light around the face of the instrument while the lower portion is provided with a reflection baffle 18 in the rear thereof, baffle 18 being positioned close against the bevel surface of the instrument for preventing light from being reflected from the surface into the eyes of the operator. A conductor 19 is connected between one terminal of each of the lamp sockets 15 and a contact pin assembly 21, the other terminal of each of the sockets being grounded to the panel 11 as disclosed in Patent No. 2,401,867 (see Fig. 2). Assembly 21 comprises an insulating member 21a having cutout 26a containing contact pin 26 in contact with conductor 19.

Referring now to Fig. 4, there is shown the electrical connection between contact pin assembly 21 and the power source which is completed upon securing the cover 13 to the panel 11. Mounted on panel 11 is a conducting contact sheet 22, preferably of metal, surrounded by an inner and outer insulating layer, 23 and 24, respectively. Outer layer 24 has a cutout 25 in the upper portion thereof whereby securing of cover 13 to panel 11 causes contact pin 26 of contact pin assembly 21 to contact sheet 22, the connection between sheet 22 by wiring 22a and the power source, not shown, may be made in any suitable manner.

An alternative electrical connection is disclosed in Fig. 5, wherein one terminal of the lamp sockets are interconnected by means of a conductor 59 and a lead 51 connected to conductor 59 is adapted to be connected to one side of the power source. Lead 51 may be provided with a detachable connection, if desired, to act as a switch.

It is understood that the type of shield or cover may be varied in design to meet the need of different type instruments and that the shield

metallic, which is capable of being worked into the desired shape. The individual cover is particularly useful when it is desired to provide lighting for a single instrument which is separate from the other instruments on the board.

Obviously many modifications and variations of the present invention are possible in the light of the above teachings. It is, therefore, to be understood that within the scope of the appended claims the invention may be practiced otherwise than as specifically described.

The invention described herein may be manufactured and used by or for the Government of the United States of America for governmental purposes without the payment of any royalties thereon or therefor.

What is claimed is:

1. The combination comprising an instrument board of electrical conducting material adapted for mounting instruments thereon, a cover for a single instrument mounted on said board in grounded relation therewith and adapted to fit over the face of an instrument, lamp means mounted on said cover and having one terminal thereof grounded to said cover, an insulated conducting plate positioned between said cover and board, said plate having a contact portion, a contact pin connected to the other terminal of said lamp means and insulatedly mounted on said cover rearwardly thereof, and said pin and plate contact portion being arranged relative to each other whereby the lamp circuit is completed when the cover is mounted on the board with the plate positioned therebetween.

2. The combination comprising an instrument board of electrical conducting material adapted for mounting instruments thereon, a cover for a single instrument mounted on said board in

grounded relation therewith and adapted to fit over the face of an instrument, lamp means mounted on and rearwardly of said cover and having one terminal thereof grounded to said cover, a conducting plate positioned between said cover and board, insulating means provided on each side of said plate insulating the plate from the cover and board, said plate having a contact portion on the side of the plate adjacent said cover, contact pin means connected to the other terminal of said lamp means and insulatedly mounted on said cover rearwardly thereof, and said pin means contacting the plate contact portion thereby completing the lamp circuit.
